A. E. RUTH,
RATCHET COMPOUND SPUD WRENCH,
APPLICATION FILED MAY 14, 1915.

1,155,960.

Patented Oct. 5, 1915.

UNITED STATES PATENT OFFICE.

ANDREW E. RUTH, OF BALTIMORE, MARYLAND.

RATCHET COMPOUND SPUD-WRENCH.

1,155,960.

Specification of Letters Patent.

Patented Oct. 5, 1915.

Application filed May 14, 1915. Serial No. 28,057.

To all whom it may concern:

Be it known that I, ANDREW E. RUTH, a citizen of the United States, residing at Baltimore, in the State of Maryland, have invented a new and useful Ratchet Compound Spud-Wrench; and I do hereby declare the following to be a full, clear, and exact description of the invention, such as will enable others skilled in the art to which it applies to make and use the same.

This invention relates to an improved ratchet multiple spud wrench especially adapted for connecting and disconnecting a union or ground nipple or spud to a radiator.

One of the objects of the invention is to provide a wrench member having a multiplicity of nipple or spud engaging devices, whereby spuds or nipples of different sizes may be connected and disconnected to radiators, said wrench member having ratchet means, whereby an intermittent motion may be imparted to the wrench member.

Another object of the invention is that the spud or nipple engaging wrench section vary in sizes substantially from the center of the wrench member toward its opposite end.

Another object of the invention is the provision of oppositely disposed elongated grooves or recesses upon the spud or nipple engaging wrench sections, to receive diametrically oppositely disposed lugs on the interior of the nipple or spud, whereby the same may be connected to the radiator or disconnected therefrom.

Another object of the invention is that said lug engaging grooves or recesses of the wrench sections are of considerable width, in order to permit of a partial play of the wrench member, in order to enable the spud or nipple to be easily started when connecting or disconnecting the same. In other words, by the provision of such a play a jolt or sudden knock may be given the spud or nipple, to overcome the frictional binding of the nipple or spud threads and the threads in the wall of the radiator.

In practical fields the details of construction may necessitate alterations, falling within the scope of what is claimed.

The invention comprises further features and combination of parts, as hereinafter set forth, shown in the drawings and claimed.

In the drawings:—Figure 1 is a view in perspective of a portion of a radiator, showing the improved spud or nipple wrench in

the act about to be received by the spud or nipple for disconnecting the same. Fig. 2 is a vertical sectional view through the ratchet mechanism of the wrench, showing the spud wrench in elevation. Fig. 3 is a sectional view on line 3—3 of Fig. 2. Fig. 4 is a view in side elevation of the spud or nipple wrench, showing the ratchet casing and its handle broken off.

Referring to the drawings 1 designates a wrench member, which is provided with a plurality of spuds or nipple engaging wrench sections 2, 3, 4, 5 and 6, which respectively vary in sizes in cross section, so as to engage different sizes of spuds, or ground nipples, or unions 7. Such spuds, nipples or unions are provided upon their interiors with diametrically oppositely disposed lugs 8. Each of the sections from 2 to 6 inclusive are provided with diametrically oppositely disposed grooves or recesses 9. These grooves 9 are wider than the thickness of the lugs 8, so that the wrench member 1 may have a slight play or movement, incident to one wall or the other of any one of the grooves or recesses 9 coming in contact with one side or the other of each of said lugs, so as to impart a sudden jolt or jar upon the lugs, in order to overcome the frictional binding of the interengaging threads of the nipples, spuds or unions and the radiator. Substantially the central portion of the wrench member 1 is provided with an integral disk 10 having ratchet teeth 11. The disk 10 fits an annular casing 12, which is open sided as shown. However, one of the open sides is provided with an annular flange 13, against the inner face of which one side of the disk 10 engages. An annular ring plate 14 is secured to the other side of the casing by the screws or other suitable means 15, for retaining the disk in the casing, so that the casing may move on the disk. The casing is provided with a hollow extension 16, in the bore or chamber 17 of which a ratchet plunger dog 18 is mounted having a beveled portion 19, so that the dog will slip by or over the teeth of the disk 10 when the casing is moved in one direction, but when the casing is moved in the opposite direction, the dog will engage the ratchet teeth, so that the casing will move with the disk, thereby imparting an intermittent motion to the wrench member 1. The plunger dog has a shank or rod 20 connected to it, which shank or rod passes

through a tubular handle 21, which is threaded at 22 into the extension 16, and the upper end of the rod or shank 20 is provided with a knob or button 23, so as to raise 5 the dog out of engagement with the teeth of the disk 10, for reversing its position, so that it may ratchet over the teeth in the opposite direction. In order that the dog 10 may yieldably ratchet over said teeth a suitable coil spring 24 is mounted in the bore or chamber 17, between the dog and the lower end of the tubular handle 21.

In operation, either one or the other of 15 said sections 2 to 6 inclusive of the wrench member is inserted in the spud, nipple or union, in order that the lugs will engage the recesses or grooves 9 of the sections, after which an intermittent motion is imparted to the wrench member, thereby connecting or 20 disconnecting the spud or ground nipple to or from the radiator. The grooves or recesses are of greater width than the lug, so that one wall or the other of each of the 25 recesses will suddenly contact with its respective lug, so as to impart a sudden jar or jolt to the spud, to overcome the frictional binding of the interengaging threads of the spud and the radiator.

The inventor is well aware that spud 30 wrenches have heretofore been used and patented, but there has been great difficulty in turning the wrench member, for instance in using a pipe or other wrench on the spud wrench member, every now and then a new 35 grip on the member must be exerted, and even when securing a good grip it has been found very difficult to turn the spud wrench member, in other words, to start the spud. The inventor is also well aware that intermittent ratchet devices have been produced, 40 but as far as the inventor can ascertain there is no intermittent ratchet device provided that will fit a spud wrench member for turning the same, and furthermore, there is no tool found in the commercial field, in 45 which the spud wrench member is combined with an intermittent ratchet device, that will easily and expeditiously start and unscrew a spud or nipple with ease and convenience. Moreover, the inventor is not 50 claiming the broad or generic idea of a spud wrench member, nor is he claiming the broad combination of a spud wrench member and an intermittent ratchet device. 55 For instance, the inventor is not claiming such structure in the terms following: "A spud wrench member and an intermittent

ratchet device". However, the inventor is claiming an essential construction of spud wrench member, as set forth in the claims, 60 in combination with means broadly to impart an intermittent motion to the member.

The invention having been set forth, what is claimed as new and useful is:—

1. In combination, a wrench member having a multiple of spud or nipple engaging sections varying in sizes substantially from the central portion of the wrench member toward its opposite ends, each of said spud or nipple engaging sections having diametrically oppositely disposed grooves to receive diametrically oppositely disposed lugs on the interior of the spud or nipple, said grooves being of sufficiently greater width than the width of said lugs to permit of 75 looseness of play with the lugs.

2. In combination, a wrench member having a multiple of spud or nipple engaging sections varying in sizes substantially from the central portion of the wrench member 80 toward its opposite ends, each of said spud or nipple engaging sections having diametrically oppositely disposed grooves to receive diametrically oppositely disposed lugs on the interior of the spud or nipple, said 85 grooves being of sufficient width to permit the lugs to have looseness of play therein, and means for imparting an intermittent motion to the wrench member.

3. In combination, a wrench member having a multiple of spud engaging sections of varying diameters in cross section substantially from the central portion of the wrench member toward its opposite ends, each of said spud engaging sections having diametrically oppositely disposed grooves to receive diametrically oppositely disposed lugs on the interior of the spuds, the groove of one section being alined with the groove of each of the other sections, and varying in widths, 95 each set of grooves being of greater width than the width of said lug to permit of a slight play of the wrench member so as to impart a jarring action on the spud to start the same, and means for imparting an intermittent motion to the wrench member.

In testimony whereof I have signed my name to this specification in the presence of two subscribing witnesses.

ANDREW E. RUTH.
